UNITED STATES PATENT OFFICE.

JOHN DAVIDSON, JR., OF TRENTON, NEW JERSEY, ASSIGNOR TO AMERICAN TELEPHONE AND TELEGRAPH COMPANY, A CORPORATION OF NEW YORK.

TELEPHONE SYSTEM.

Application filed August 10, 1920. Serial No. 402,681.

To all whom it may concern:

Be it known that I, JOHN DAVIDSON, Jr., residing at Trenton, in the county of Mercer and State of New Jersey, have invented 5 certain Improvements in Telephone Systems, of which the following is a specification.

This invention relates to telephone systems and more particularly to systems in 10 which the signals for a plurality of trunk lines extending between widely separated offices are controlled over a single signaling path common to such trunk lines.

Heretofore some systems of this character 15 have been arranged for manual trunking only and have employed at opposite ends of the signaling path, switching means for temporarily rendering the common signaling path individual to the various trunk lines 20 served thereby. This individualizing apparatus comprises means for translating into code signals the signals initiated by the different trunk lines, means for transmitting over the signaling path the code 25 signals which are individual to the trunk lines, and means for receiving and translating the code signals into signals individual to the respective trunks.

It is desirable to arrange the trunk circuits so that the incoming terminals thereof 30 may be extended automatically to idle responsive means without sacrificing the efficiency of the trunk circuits for speech transmission. It is therefore the object of the 35 present invention to provide improved signaling means for systems of this character by means of which code impulses are transmitted over a common signaling path for controlling the association of responsive 40 means with the incoming end of any one of a plurality of trunk circuits.

For the attainment of the object of the invention, there is provided at the originating end of the trunk lines and associated signaling path, apparatus individual to each trunk line responsive to the seizure of a trunk, for setting up and transmitting a code of impulses over the common signaling path. These impulses are received at the 45 terminating end of the signaling path and translated into a switching impulse for starting up a plurality of trunk finding switches for associating responsive means with the trunk taken for use at the originating 50 end of the signaling path.

Apparatus individual to each trunk line is also provided at the terminating end of the trunk lines and associated signaling path for setting up and transmitting over the common signaling path codes of impulses 60 which are received at the originating end of the signaling path and translated into signaling impulses for controlling the operation of a supervisory signal associated with the outgoing end of the toll trunk taken for use, this supervisory signal being arranged to operate as soon as the responsive means has been associated with the terminating end of the trunk circuit which 65 has been selected for use, and to cease operating as soon as the responsive means again becomes disassociated.

By the employment of the common signaling path for transmitting all control and supervisory signals, it is possible to freely 70 use the trunk for telegraphic purposes, to prevent tying up expensive apparatus permanently to the particular toll trunk and thereby attain a more efficient use of the signaling apparatus, and to permit the use 75 of as many telephone repeaters in the toll trunk as are found necessary for efficient transmission.

The invention may be more readily understood by reference to the following description considered in connection with the accompanying drawing in which Figure 1 shows the calling end of a cord circuit at an originating toll operator's position, the calling jack of one of the toll trunks appearing before the toll operator's position, relay mechanism individual to the outgoing end of the toll trunk, and code impulse sending mechanism associated with the outgoing end of the signaling path common to 80 a plurality of toll trunks; Fig. 2 shows the terminating end of a toll trunk which may be extended in any desired manner, relays individual to the incoming end of the toll trunk, and one of a group of finder switches 85 for associating responsive means with the terminating end of any one of a plurality of toll trunks; and Fig. 3 shows a receiving and translating mechanism associated with the distant terminating end of the signaling path for receiving code impulses incoming 90 over the signaling path and for controlling the individual relays of the associated group of trunks.

Figs. 1, 2 and 3 arranged with Fig. 2 at 110

the right of Fig. 1 and Fig. 3 beneath Fig. 2 shows so much of a complete organization of circuits as is necessary to illustrate the manner in which a connection may be established from a toll operator's cord circuit in an originating office X to responsive means 220 in a terminating office Y.

Referring to the drawings, there is shown a toll trunk line L comprising two talking conductors extending from the originating office X to the terminating office Y. At the originating office X, there are provided a plurality of toll cords one of which is shown at F, by means of which a connection may be established with the trunk line L. The trunk line L may terminate in the office Y in any connecting means desired such as a selector switch, a plug, or in a jack appearing before an operator and also terminates in multiple terminals appearing before a plurality of finder switches, one of which is shown at K, by means of which the trunk line may be connected with an idle responsive means 220.

25 The supervisory signals for supervising the association of the finder switches K with the terminating ends of the toll trunks and for apprising the originating operator that such association has taken place, may be controlled over a single signaling path common to the trunk lines and comprising a conductor Q extending from the originating office X to the intermediate office Y, which path is shown as having a grounded return. 30 The signaling conductor is arranged in a well known manner for duplex operation for which purpose there is provided at the ends of the conductor, artificial balancing lines AL and differentially balanced relays 25" and 25'. Each end of the common signaling conductor Q is connected with a commutator for sending and receiving signals. These commutators are preferably of the well known start-stop type of distributors employed in connection with printing telegraph systems. Such commutators are disclosed in the Patent No. 1,387,284 to MacDougal and MacPherson, issued August 9, 1921.

35 The commutator at office X comprises a sending distributor S for transmitting signals over the conductor Q, to the office Y, and a receiving distributor R indicated by the dotted rectangle and of exactly the same construction as the receiving distributor R' shown in Fig. 3 for receiving signals transmitted over conductor Q from office Y, and similarly the commutator at the office Y comprises a sending distributor S' shown in the dotted rectangle and of exactly the same construction as the sending distributor S shown in Fig. 1 and a receiving distributor R', for receiving signals from the office X over the conductor Q. These commutators at both offices X and Y are of the same construction 40 and a description of the sending commutator

S and of the receiving commutator R' will be sufficient. The sending and receiving distributors S and R each comprise a series of stationary rings, some of which are continuous and others segmented, and a common shaft on which are mounted brush arms normally held from rotation by the respective armatures of two separately controlled release magnets. The outer end of each brush arm is insulated from the inner end so that each brush arm controls two separate groups of circuits. Between the common shaft and each brush arm there is provided frictional clutch mechanism (not shown) by means of which the constantly rotating shaft, causes the rotation of each brush arm when released. The face of the sending commutator S is stationary and is provided with a sending ring 14, a restoring segment r, a start segment s, and individual sending segments 1 to 6 inclusive for controlling the signaling impulses over the signaling conductor Q, and with a common ring 15 and segments 16, 17 and 18 for controlling local circuits. The face of the receiving distributor R' is also stationary and provided with a common receiving ring 19 and individual receiving segments 21 to 26 inclusive for selecting a circuit according to the code of signals received over the signaling conductor Q, segments 27 and 28 through which the selected signal receiving circuit is completed, segments 29 and 30 for controlling the circuit of the associated release magnet RRM and a ring 31 and segment 32 for controlling a local circuit.

45 At the originating office X, the common signaling conductor Q is connected to the common sending segment 14, while the normal contact of the differential polarized relay 25" is connected with the common receiving segment of receiver R, corresponding to segment 19 of receiver R', and the alternate contact is connected with the segment of distributor R which corresponds to segment 29 of distributor R'. When relay 25" is operatively energized, the release magnet of the receiving distributor R is energized to release the brush arm of the receiving distributor. At the terminating office Y, the conductor Q is connected with the common sending segment of sending distributor S' which corresponds with segment 14 of sending distributor S while the normal contact of the differential polarized relay 25' is connected with the common receiving segment 19 of the receiving distributor R', and the alternate contact of this relay is connected with the segment 29. When the relay 25' is operatively energized, the release magnet RRM is energized releasing the brush arm 10.

50 The codes of signals transmitted over the common signaling conductor Q by the sending distributors S, S' are determined by 120

- the polarity of current connected with the individual sending segments of the respective sending distributors S, S'. These polarities are determined by the position of the brushes of automatic selector switches, 5 the selector switch which is associated with the distributor S being shown in Fig. 1 and designated G. These automatic selector switches are common to a plurality of toll 10 trunk lines and are each provided with 8 brushes a to h inclusive mounted upon a single shaft driven by a motor magnet MM initially controlled by start relay 100 connected in the start conductor or start lead 15 ST common to a group of trunk lines. Brushes c to h inclusive are connected directly with the respective individual sending segments 1 to 6 inclusive of the sending distributor S. Brush a is connected with 20 one winding of stop relay 101 which controls the circuit of the motor magnet MM and the energization of the release magnet SRM of the sending distributor S. Brush b is connected with a contact of relay 102 for 25 the purpose of assisting in the control of the switch as will more fully appear hereinafter. Relay 102 and release relay 103 associated with the automatic selector switch G are controlled by the sending distributor S for reasons which will more fully hereinafter appear. A plurality of contacts equal to twice the number of toll trunk lines to which the selector switch G is common is associated with each brush. The contacts associated 35 with the different brushes are mounted at different levels in position to be engaged by the respective brushes as they are rotated by the motor magnet MM. Two correspondingly positioned contacts of all levels are allotted to each trunk line, for example, the first two contacts may be allotted to trunk #1. The two contacts on levels a and b allotted to each trunk line are connected to 40 relays individual to and associated with the outgoing end of the trunk line. The trunk line L has been shown associated with the first two contacts of each level of switch G. As shown, relays individual to the outgoing end of this trunk line are connected by 45 means of individual signal control leads 104, 105 and restoring leads 106 and 107 with the allotted contacts accessible to the brushes a and b, signal control leads 104 and 105 being connected to the respective first and second 50 contacts of the level to which brush a has access, and restoring conductors 106 and 107 to the respective first and second contacts of the level to which brush b has access. Each trunk line is provided with similar signal 55 control and restoring leads at the office X similarly connected with the selector switch G. The automatic selecting switches are provided with sufficient contacts to accommodate 30 trunk lines. To the contacts of 60 the levels to which brushes a to h have ac- cess, allotted to the respective trunk lines, are connected sources of current of positive or negative potential so as to provide distinctive code signals for each of the 30 trunk lines. 70
- The selector switch associated with the sending distributor S' is associated with the incoming ends of the group of toll trunks in exactly the same manner as selector switch G is associated with the outgoing ends of the trunks, the polarities connected with the individual sending segments of the sending distributor being determined in exactly the same manner as heretofore described in connection with the selector switch G. 75
- In order that the signals transmitted from the originating office X of the sending distributor S and received at the office Y may be utilized, there are provided at the office Y six locking relays 41 to 46 inclusive having energizing windings connected with the respective individual receiving segments 21 to 26 of the receiving distributor R'. When a negative impulse is transmitted from a particular individual sending segment the relay connected with the corresponding individual receiving segment will be energized and locked up. Relays 41 to 44 control a plurality of receiving and selecting relays 50 to 64 inclusive which co-operate with relay 45 to select a signal control circuit individual to a particular trunk line, while relay 46 controls the polarity of current connected with the selected signal control circuit. The individual signal control circuits are connected with contacts of relays 57 to 64 inclusive. Similar equipment is provided at the originating office X for utilizing the signals transmitted from the terminating office Y over the common signal conductor Q and which is designated by the dotted rectangle R. 90
- The finder switch K shown in Fig. 2 is of the well known rotary step-by-step type and is employed to connect a responsive means indicated by the dotted rectangle 220' with the incoming end of a toll trunk line L. This responsive means may be of any desired character, for example, an impulse repeater such as described in my copending application Serial No. 402,632, filed August 10, 1920. 100
- Having in mind this brief description of the apparatus of the system shown in the drawings, it is thought that the invention will be more fully understood from the description of the operation of the system shown, and therefore a description of the method of extending a connection from the toll operator's cord circuit F over toll trunk line L to the responsive means 220' shown in Fig. 2, will be explained in detail. 115
- The operator at the originating office X in response to a call incoming to her position inserts the calling plug P of the cord circuit 120
- 125
- 130

F in the jack J of the idle toll trunk L which is selected by testing in the well-known manner. A circuit is now established extending from grounded battery through the winding 5 of marginal sleeve relay 118, over sleeve conductor 119, through the sleeve contact of plug P, the sleeve contact of jack J, the winding of relay 108 and thence to ground through the winding of marginal relay 109. 10 Relay 108 energizes in this circuit, but owing to their marginal nature relays 109 and 118 do not energize at this time. Relay 108, upon energizing, closes a circuit for relay 115, which circuit may be traced from grounded 15 battery, left armature and back contact of relay 114, winding of relay 115, front contact and armature of relay 108 to ground, and also closes a circuit for relay 110 which circuit may be traced from grounded battery 20 through the inner left-hand armature and back contact of relay 111, the winding of relay 110 and thence to ground through the front contact and armature of relay 108. Relay 110 upon energizing closes a locking 25 circuit for itself extending from grounded battery through its inner left-hand armature and front contact, the winding of relay 110 and thence to ground at the armature and front contact of relay 108. Relay 110 also 30 closes an energizing circuit for relay 111 which may be traced from grounded battery through the outer left-hand armature and front contact of relay 110 and thence to ground through the left-hand winding of relay 111. 35 Relay 111 upon energizing closes a locking circuit for itself extending through its inner left-hand armature and front contact, and opens at the back contact of this armature, the initial energizing 40 circuit of relay 110.

Upon the energization of relay 111, ground is connected to the start conductor ST over the intermediate left-hand armature and front contact of relay 111, the 45 right-hand armature and back contact of relay 112, and the right-hand armature and back contact of relay 113, and ground is connected to signal control conductor 105 over the outer left-hand armature and front contact of relay 111, the outer right-hand armature and front contact of relay 110, the left-hand armature and back contact of relay 112 and the outer left-hand armature and back contact of relay 113.

55 Relay 100 now energizes over conductor ST and closes a circuit for the motor magnet MM extending from grounded battery through the armature, contact and winding of magnet MM, the left-hand armature and back contact of stop relay 101 and the front contact and armature of relay 100. Motor magnet MM upon energizing in this circuit advances the brushes of the selector switch G over their respective levels of contacts 60 until brush *a* finds a grounded conductor

105 corresponding to the toll trunk which has been taken for use by the toll operator. Assuming that the conductor 105 corresponding to the toll trunk L is the first grounded conductor to be encountered by the brush *a*, a circuit is established for the stop magnet 101 extending from grounded battery through the left-hand winding of this stop relay, through the brush *a* over conductor 105, and thence to ground as previously traced at the outer left-hand armature of relay 111. The stop magnet 101, upon energizing, opens the circuit of the motor magnet MM and thereby arrests the movement of switch G. Relay 101 also 70 closes a locking circuit for itself extending from grounded battery at the armature and back contact of release relay 103 through the inner right-hand armature and front contact of relay 101 and the right-hand winding thereof to ground. Relay 101 also 75 closes a circuit for release magnet SRM of the sending distributor S which circuit extends from grounded battery through the ring 15, the inner brushes on the brush arm 9, segment 16, the front contact and outer right-hand armature of relay 101 and thence to ground through the winding of the release magnet SRM. The attraction of the 80 armature of release magnet SRM upon the energization thereof, releases the brush arm 9 which is thereupon rotated through a complete cycle, at the end of which the brush arm is stopped in its normal position. The brush arm 9, in being rotated, first 85 engages start segment *s* thereby connecting positive current with the common signaling conductor Q.

Brush arm 9 then moves beyond segment 105 16 thereby opening the energizing circuit of, and causing the deenergization of release magnet SRM which restores its armature to normal position preparatory to stopping the brush arm when it reaches its normal position. Upon the assumption that the switch G stopped with its brushes in engagement with the first of the two contacts in the several levels allotted to trunk line L, it will be noted that positive current is connected with such first contacts of levels *c*, *d*, *f*, *g* and *h*, while negative current is connected with such first contact of level *e*. When the inner brushes on brush arm 9 engage segment 17, a circuit is closed extending from battery through ring 15, the inner brushes on arm 9, segment 17 and thence to ground through the winding of relay 102. This relay upon energizing closes a circuit 110 extending from grounded battery through the armature and back contact of relay 103, the armature and front contact of relay 102 over brush *b* of switch G, conductor 106, winding of relay 113, right-hand armature and back contact of relay 112 and thence to 115 ground through the left-hand intermediate 120 125 130

armature and front contact of relay 111. Relay 113 energizes in this circuit and at its inner left-hand armature establishes a locking circuit for itself independent of the circuit extending through brush *b* of switch G, at its outer left-hand armature and back contact opens the circuit extending over conductor 105, and at its right-hand armature and back contact opens the starting conductor ST.

As the brush arm 9 successively moves its brushes over the individual sending segments, 1 to 6 inclusive, current sources of the polarity connected with these segments are successively connected to the conductor Q. When the brush arm 9 moves its brushes out of engagement with segment 17, the energizing circuit of relay 102 is opened and upon the engagement of the inner brushes on brush arm 9 with segment 18, a circuit is established for release relay 103, which extends from grounded battery through ring 15, the inner brushes on arm 9, segment 18 and thence to ground through the winding of relay 103. Relay 103, upon its energization, opens the locking circuit of relay 101 whereupon this relay releases. As the brushes on arm 9 move out of engagement with segment 18, release relay 103 is deenergized. When the brushes on brush arm 9 engage the restoring segment *r*, current of negative polarity is connected with the common signaling conductor Q and the selector switch G is now in condition to be seized by another trunk since the trunk line L is now disconnected therefrom and the sending distributor S is in normal condition.

The connection of positive current from segment *s* with conductor Q does not affect differential polarized relay 25" in office X, but causes the operation of the differential polarized relay 25' at the terminating office Y, over a circuit extending from positive battery through segment *s*, the outer set of brushes on arm 9, the common sending ring 14, and the junction point between the windings of differential polarized relay 25", then by one path through the lower winding of relay 25" and artificial line AL to ground, and by another path through the upper winding of relay 25", conductor Q both windings of the differential polarized relay 25' and the artificial line to ground. The operation of relay 25' establishes a circuit extending from grounded battery through the alternate contact of relay 25', segment 29, the outer set of brushes on arm 10 of the receiving distributor switch R', segment 30 and thence to ground through the winding of release magnet RRM. The attraction of the armature of the release magnet upon the energization thereof releases the brush arm 10 which is thereupon rotated through a complete cycle, at the end of which the brush

arm is stopped in its normal position. As the brush arm 10 moves its brushes out of engagement with segments 29 and 30, the circuit extending through the winding of release magnet RRM is opened, and the magnet, deenergizes permitting the restoration of its armature to normal position preparatory to stopping the brush arm 10 when it reaches its normal position. When the brush arm 10 moves its inner set of brushes into engagement with the segment 32, a circuit is established extending from grounded battery, through the ring 31, the inner set of brushes on brush arm 10, segment 32 and thence to ground through the winding of relay 82. Relay 82 thereupon energizes connecting a holding ground to the conductor 83, through its armature and front contact, which conductor is connected in parallel to the locking circuits of relays 41 to 46 inclusive. The armature of the differential polarized relay 25' remains in its alternate position as long as positive current is connected with the other end of the conductor Q and moves to its normal position whenever negative current is connected with the other end of conductor Q.

The brush arms 9 and 10 are rotated synchronously, and while brush arm 9 positions its brushes in engagement with segment 3 of the sending distributor S to which negative current is connected, the armature of relay 25' moves to its normal position and brush arm 10 positions its brushes in engagement with the receiving segment 23. Relay 43 is thereupon energized over a circuit extending from grounded battery through the normal contact of relay 25', segment 19 of the distributor R', the outer set of brushes on brush arm 10, segment 23 and thence to ground through the lower winding of relay 43. This relay, upon energizing, locks itself to the grounded conductor 83, through its upper winding and its upper armature contacts. At its lower armature and front contact, relay 43 closes a circuit extending from grounded battery through the windings of relays 52 and 51 which thereupon energize. When the brush arm 10 positions its brushes upon the segments 27 and 28, just prior to reaching its normal position, a circuit is established extending from grounded negative battery through the lower armature and back contact of relay 46, through segment 27, the outer set of brushes on brush arm 10, segment 28, the lower armature and back contact of relay 45, the lower armature and back contact of relay 50, the lower armature and front contact of relay 51, the upper armature and back contact of relay 53, the upper armature and back contact of relay 58, thence over conductor 300 and to ground through the left-hand winding of relay 200 and right-hand winding of relay 201. As soon as brush arm 10 moves its brushes be-

yond the segments 27 and 28, the circuit extending through the winding of relay 82 is opened and this relay deenergizes, opening the locking circuit of relay 43 and thereby 5 the circuit through the windings of relays 51 and 52. The circuits of the receiving distributor R' are now in normal position in readiness for the receipt and translation of other code signals. It is to be noted that 10 during the rotation of the receiving distributor, relays 41, 42, 44, 45 and 46 were not energized inasmuch as relay 25' was holding its armature against its alternate contact at the time the brushes on switch arm 10 were 15 passing over segments 21, 22, 24, 25, and 26 connected respectively to these relays.

Relay 200 at the terminating office Y upon energizing over the circuit traced through conductor 300, closes a locking circuit for 20 itself extending from grounded battery through its right-hand winding and to ground through its inner right-hand armature and front contact. The energization of relay 201 is without effect at this time and 25 this relay deenergizes as soon as the receiving distributor R' reaches normal position and opens the circuit over conductor 300. Relay 200, upon energizing, also bridges the polarized relay 202 across the 30 incoming end of the toll trunk line L, over a circuit extending through the outer armature and front contact of relay 200, and at its inner armature and front contact closes a circuit extending through the right-hand 35 armature and back contact of relay 201, and through the winding of slow release relay 203. The energization of relay 203 is without a function at this time. A circuit is also established from battery at the right- 40 hand armature and back contact of relay 221, through the winding of relay 222, conductor 223 and thence to ground at the inner armature and front contact of relay 200.

Relay 222 energizes in this circuit if relay 45 221 is at the time deenergized, and closes a circuit extending from grounded battery through the winding of starting relay 224, the armature and front contact of relay 222, and thence through the left-hand armature 50 and back contact of relay 225 and resistance 226 to ground. Selectable potential is also connected over the circuit above traced to the lowermost bank contact 227 of finder switch K.

Upon the energization of relay 224, a circuit is closed through the motor magnets 228 of all finder switches which are at the time idle. A circuit for the motor magnet of 55 finder switch K shown in Fig. 2, may be traced from grounded battery through the motor magnet 228, the armature and back contact of this magnet, the outer right-hand armature and back contact of stop relay 229, and thence to ground at the armature and 60 front contact of relay 224. The finder

switches which are started will continue to move their brushes over their respective banks of contacts which are multiplied to the thirty trunks of the group to which these finders are assigned until one of the 70 finders positions its brushes upon the set of bank contacts individual to the trunk line L which has been taken for use. Assuming that the switch K is the first finder switch to engage these contacts, a circuit 75 will be established from grounded battery connected through the circuit previously traced to the bank contact 227, thence over brush 230 and to ground through the winding of stop relay 229. Relay 229 energizes 80 in this circuit opening at its outer armature and back contact the circuit extending through motor magnet 228, and at its inner armature and front contact closes a circuit 85 extending from grounded battery through the winding of relay 231 and thence to ground through the inner armature and front contact of relay 229.

Relay 231 upon energizing connects the responsive means 220' over its armatures 90 and front contacts, brushes 232 and 233 of finder switch K, contacts 234 and 235 with which they are in engagement, thence over conductors 236 and 237, through the inner and outer left-hand armatures and back contacts of relay 221 to the tip and ring conductors of the toll trunk L. A circuit is also closed at this time from grounded battery through retardation coil 238, the upper armature and front contact of relay 231, 100 brush 232, contact 234, conductor 236, the inner armature and back contact of relay 221, the inner armature and back contact of relay 205, the upper right-hand winding of repeating coil 214, the winding of polarized relay 202, the outer armature and front contact of relay 200, the lower right-hand winding of repeating coil 214, the outer armature and back contact of relay 205, the 105 outer left-hand armature and back contact of relay 221, conductor 237, back contact 235 of finder switch K, brush 233, the lower armature and front contact of relay 231, retardation coil 239 and thence to ground 110 through the winding of relay 229. A circuit is also established at this time for relay 225 which circuit may be traced from grounded battery through the right-hand armature and back contact of relay 221, winding of relay 225, bank contact 240 of 115 finder K, brush 241 and thence to ground through the inner armature and front contact of relay 229. Relay 225 upon energizing opens the circuit of relay 224 which, if there are no other incoming calls on other trunks of the group at this time, will deenergize opening the starting circuits of all other finder switches which have been started to hunt for the calling trunk.

When relay 231 energized and established 120

a circuit through the winding of polarized relay 202, relay 202 energized in such a manner as to move its armature into engagement with its lower contact thereby closing a circuit for relays 207 and 208 and slow releasing relay 206. Relay 207 is slightly slow-to-energize and to diagrammatically indicate this on the drawing, said relay is shown with an arrow passing through its armature pointing in the direction in which the armature slowly moves. Other relays shown on the drawings with an arrow pointing in the opposite direction are slow-to-release. The circuit for relay 206 may be traced from grounded battery through the winding of this relay, the armature and lower contact of relay 202 and thence to ground at the inner armature and front contact of the relay 200. The circuit of relay 207 may be traced from grounded battery through the winding of this relay, the normally closed make-before-break armature contacts of this relay, the right-hand armature and back contact of relay 209, the outer right-hand armature and back contact of relay 210, the armature and lower contact of relay 202, and thence to ground at the armature and front contact of relay 200. Relay 207 upon energizing closes a locking circuit for itself through its right-hand armature and make contact, the outer left-hand armature and back contact of relay 211 and thence to ground over the circuit previously traced through the armature and lower contact of relay 202. Relay 207 thus remains under the control of relay 202 until relay 211 is operated. The circuit of relay 208 may be traced from grounded battery through the winding of relay 212, the outer left-hand armature and back contact of relay 209, the winding of relay 208, the break contacts of its inner right-hand armature, the left-hand armature and back contact of relay 207, the right-hand armature and back contact of relay 209 and thence to ground over the circuit previously traced through the armature contacts of relay 202. Since relay 207 is slightly slow to energize, the circuit of relay 208 is established before relay 207 energizes to open its left-hand armature contacts. Relay 208, upon energizing, in the circuit previously traced closes a locking circuit for itself extending through the winding of the start relay 212 of sending distributor S' which relay corresponds to relay 100 of the sending distributor S and thence through its own winding and the make contacts of its inner right-hand armature, to ground.

Relay 208, upon energizing, closes a circuit for relay 220, extending from grounded battery through the winding of relay 220, the left-hand armature and back contact of relay 219 and thence to ground at the inner left-hand armature and front contact of relay 208. Relay 220 energizes in this circuit and closes a locking circuit for itself extending through its armature and front contact, through the winding of relay 219, through the inner right-hand armature and back contact of relay 210, and to ground at the inner armature and front contact of relay 200. Relay 219, however, does not energize in this circuit since its winding is shunted by ground at the armature contact of relay 208. The energization of the start relay 212 of the sending distributor starts up the sending distributor in a manner exactly similar to the starting of sending distributor S hereinbefore described, and causes the transmission of a code of signals over the conductor Q, and through the polarized relay 25'. The sending distributor S' makes a complete revolution and after leaving normal position closes a circuit over conductor 106' through the winding of relay 209, which relay upon energizing opens the locking circuit of relay 208. Relay 207 remains locked through the lower contact of relay 202. The sending distributor S' is restored to normal and is ready for the transmission of another code of impulses. The circuit over conductor 106' is closed at the sending distributor S' in exactly the same manner as the circuit over conductor 106 is closed at the sending distributor S.

The code of impulses is received by the receiving distributor R and translated in a manner exactly similar to the operation of the receiving distributor R' previously described and causes the closure of a circuit over the conductor 120 to ground through the right-hand winding of relay 114. Relay 116 does not operate at this time over conductor 120 since its circuit which is normally in parallel with the winding of relay 114 is opened at this time at the armature and back contact of slow releasing relay 115. Relay 114 upon energizing in this circuit closes a locking circuit for itself extending from grounded battery through its left-hand armature and front contact, its left-hand winding and thence to ground at the armature and front contact of relay 108, and at its left-hand armature and back contact opens the circuit of slow releasing relay 115. Relay 115 however, does not close the circuit extending through the right-hand winding of relay 116 until after the momentary impulse of battery is removed from conductor 300. A circuit is closed from ground at the right-hand armature and back contact of relay 116, through the right-hand armature and front contact of relay 114, through resistance 117 and thence over the sleeve conductor of the trunk circuit L, through the sleeve of jack J, sleeve of plug P, conductor 119 and winding of marginal relay 118 to grounded battery. The connection of resistance 117 in parallel with the

windings of relays 108 and 109 changes the resistance of the sleeve circuit sufficiently to permit the operation of marginal relay 118 of the toll cord circuit F, which relay, upon 5 energizing, closes the circuit of the lamp 121, which at this time serves to give the toll operator a signal to apprise her of the fact that the finder switch K has associated the responsive means 220' with the incoming end of the toll trunk line L.

In response to the signal given by lamp 121, the toll operator proceeds to operate the responsive means 220 over the toll trunk L. This responsive means may take the 15 form of an impulse repeating device for repeating impulses out over the incoming end of the trunk circuit L at the office Y, as fully set forth in the copending application hereinbefore referred to or may be of any other 20 desired form such as an operator's head set or indicating mechanism. Since, however, this specific form of the responsive means does not constitute an essential part of the present invention, further reference 25 to such operation is not deemed necessary herein. Having operated the responsive means 220', the operator initiates the release of the finder switch K to disconnect the responsive means from the trunk circuit L by 30 releasing the key 122. This key which the operator depressed at the time she operated the responsive means 220', closed a circuit extending from grounded battery directly to the sleeve conductor 119 in parallel with the 35 winding of relay 118 which so increased the flow of current over the conductor that the marginal relay 109 energized. Relay 109, upon energizing, closes a circuit for relay 112 extending from grounded battery 40 through the winding of relay 112 and thence to ground through the armature and front contact of relay 109. Relay 112, upon energizing, opens the locking circuit of relay 113 permitting relay 113 to deenergize thereby 45 connecting start conductor ST and impulse control conductor 105 to the back contacts of the armatures of relay 112.

Upon the release of key 122, the circuit previously traced over sleeve conductor 119, 50 in parallel with the winding of marginal relay 118 is opened and relay 109 thereupon deenergizes opening the circuit of relay 112, which upon deenergizing connects the start conductor ST, and the impulse controlling conductor 105 as previously described to ground at armature contacts of relay 111. In response to the connection of conductor ST to ground, the selector switch G is started 55 to find the trunk line which is in use, and sending distributor switch S is started to send a code of impulses over the signaling path Q in exactly the same manner as described in connection with the original seizure of trunk line L. At the office Y, the 60 code of impulses is received by the receiving

distributor R' and translated into a momentary impulse of current over conductor 300 individual to the incoming end of trunk line L for causing the energization of relay 201. Since, at this time, relay 200 and slow 70 releasing relay 203 are energized, relay 201 at its left-hand armature and front contact closes a locking circuit for itself extending through its left-hand winding and to ground at the armature and front contact of slow release relay 203. At its right-hand armature and back contact, relay 201 opens the circuit of slow releasing relay 203, but relay 203 being slow to release does not open the locking circuit of relay 201 until sufficient 80 time has elapsed for a circuit to be extended from grounded battery through the winding of slow release relay 215, the right-hand armature and front contact of relay 201 and to ground at the inner right-hand armature 85 and front contact of relay 200. The operation of slow release relay 215 closes a circuit for slow release relay 216 which in turn closes a circuit for slow release relay 217 and relay 205. The purpose of the slow 90 release relays 203, 215 and 216 is to prolong the interval during which relay 205 is energized. The function of relay 205 is to transmit ringing current from the intermediate office Y to the terminal office. 95

The energization of relay 216 also closes a circuit extending from grounded battery through its inner left-hand armature and front contact, through the winding of relay 221, thence over conductor 223 to ground 100 at the inner right-hand armature and front contact of relay 200. Relay 221 upon energizing closes a locking circuit extending from grounded battery through its right-hand armature and front contact through 105 its winding and thence to ground over conductor 223. At its inner and outer left-hand armatures, relay 221 disconnects the trunk finder switch K and its associated responsive 220' from the trunk L and extends 110 the toll trunk L to the windings of relay 242, which relay may be employed for any desired apparatus such as controlling a signal at the terminating end of the trunk circuit. Relay 221 also opens the circuit 115 previously traced through relays 222 and 225 causing these relays to release. The release of relay 222 has no effect upon the circuit at this time. Relay 221 also opens the circuit of relay 229 which in turn opens 120 the circuit of relay 231, releasing the toll line finder K and rendering this finder free to be used in other connections.

The energization of relay 217 connects ground through its left-hand armature and front contact to the windings of signaling relays 206, 207 and 208 to prevent any signal from being sent back over the common signaling path by the release of relay 202 during the time that relay 205 is energized. 125

At the time the toll line finder K was disconnected from the toll trunk line L upon energization of relay 221, relay 202 was operated to close its upper contacts by reverse current flowing over the conductors of trunk L through the winding of relay 242. After an interval of time during which time the slow releasing relay 206 releases due to relay 217 opening the ground connection to relay 206 as previously described, a circuit is closed through the winding of relay 210 which may be traced from grounded battery, through the winding of the start relay 212, of sending distributor S', the outer left-hand armature and back contact of relay 209, the inner left-hand armature and back contact of relay 209, the winding of relay 210, the outer right-hand armature and back contact of relay 208, the right-hand armature and front contact of relay 219, the break contacts of relay 206, the upper contact and armature of relay 202 and thence to ground at the inner armature and front contact of relay 200. Relay 207 is released when relay 202 opens its lower contact.

The operation of the start relay 212 of the sending distributor S' as has already been described starts the sending distributor S' for transmitting a code of impulses over the signaling path Q. The energization of relay 210 through its left-hand armature and front contact connects ground to the conductor 104' for stopping the brushes of the selector switch associated with the sending distributor S' upon the second contacts of the banks to which they have access, which contacts are individual to the trunk line L. The energization of relay 210 also opens the locking circuit which has heretofore been established from battery through the winding, armature and front contact of relay 220, the winding of relay 219, the inner right-hand armature and back contact of relay 210 and thence to ground at the inner armature and front contact of relay 200. As soon as the code of signals has been transmitted over conductor Q, a momentary impulse is received from sending distributor S', over the conductor 106' as hereinbefore described for energizing the relay 209 which relay opens the circuit of relay 210, leaving the circuits at the incoming end of the trunk line in condition for the transmission of other signals.

The receiving distributor R starting up in synchronism with the sending distributor S' causes the locking up of the translation relays associated therewith and, since a code for this particular trunk comprising two positive, a negative, two positive and a negative impulse was transmitted over the signaling conductor Q, a positive impulse is transmitted from grounded battery over conductor 120 and to ground

through the right-hand winding of relay 114. This circuit is closed at the receiving distributor R in exactly the same manner as previously described in connection with circuit closed at the receiving distributor R' with the exception that since the last impulse of the group is a negative impulse, the relay corresponding to relay 46 is energized to connect positive current to the conductor 120 instead of negative current. The current flowing through the right-hand winding of relay 114 now opposes the current flowing through the locking circuit of this relay causing the de-energization of the relay and the disconnection of the shunt resistance 117 from the sleeve conductor of the trunk. Marginal relay 118 of cord circuit F thereupon de-energizes to extinguish the lamp signal 112 to give the operator a signal that the toll line finder K has been disconnected from the incoming end of the toll line L and that the toll trunk L has been cut through to the apparatus represented at 242.

When connection of the toll trunk line L is no longer desired, the operator at the originating end of the toll trunk removes the plug P of the cord circuit F from the jack J of the toll trunk, thereby opening the circuit over sleeve conductor 119, extending through the windings of relays 108 and 109. Sleeve relay 108 now deenergizes opening the locking circuit of relay 110 which upon deenergizing connects ground to the start lead ST for starting the selector G. Ground is also connected to the conductor 104 from the outer left-hand armature of relay 111 over the right-hand armature and back contact of relay 110 and the selector switch G will therefore be arrested with its brushes positioned upon the second contacts of the levels to which they have access. The sending distributor will therefore transmit a code of impulses over the path Q, comprising two positive, a negative, two positive and negative impulses. While these impulses are being transmitted by the sending distributor S' battery is connected over brush b to lead 107, in a manner similar to that in which battery was connected to lead 106, through the front contact and right-hand armature and right-hand winding of relay 111 to ground. The current through the right-hand winding of relay 111 flows differentially with respect to the current through the left-hand winding, and this relay therefore releases. The release of relay 111 releases relay 113, and the trunk L is then free to be used for other connections. The above impulses are received by the receiving distributor R' causing the energization of relays 43, 46, 51 and 52 in the same manner previously described.

Just prior to the return of brush arm 10 of the receiving distributor R' to normal

position, a circuit will be closed from positive battery, through the lower armature and front contact of relay 46, segment 27, the outer set of brushes on brush arm 10, segment 28, the lower armature and back contact of relay 45, lower armature and back contact of relay 50, lower armature and front contact of relay 51, the upper armature and back contact of relay 53, 10 the upper armature and back contact of relay 58, conductor 300 and thence to ground through the winding of relay 200. The current flowing over this circuit and through the left-hand winding of relay 200 15 is flowing in such a direction as to oppose the current flowing in the right-hand locking circuit of this relay and relay 200 will therefore be deenergized. Upon its deenergization, relay 200 opens the locking circuit 20 of relay 221 and relay 221 thereupon deenergizes opening at its left-hand armature contacts, the tip and ring conductors of the incoming end of the toll trunk. The toll trunk is now in its normal condition and all 25 apparatus associated with the outgoing and incoming ends of the toll trunk and with the outgoing and incoming ends of the common signaling path are in normal position.

What is claimed is:

- 30 1. In a telephone system, in combination, an originating office, a distant office, a plurality of trunk lines and a separate signaling path common thereto extending between said offices, means at said originating office 35 for establishing connection with any one of said trunk lines, a rotating switch at said distant office for seizing the incoming end of any one of said trunk lines, and means automatically controlled over said common 40 signaling path for initiating the movement of said trunk seizing switch and causing it to seize the trunk with which connection has been established at the originating office.
2. In a telephone system, in combination, 45 an originating office, a distant office, a plurality of trunk lines and a signaling path common thereto extending between said offices, means at said originating office for establishing connection with any one of said trunk lines, a group of trunk finding switches at said distant office for seizing the incoming end of any one of said trunk lines, and means automatically controlled over said common signaling path for initiating the movement of all idle 50 switches of said group for causing the seizure of the trunk line with which connection has been established at the originating office.
- 55 3. In a telephone system, in combination, an originating office, a distant office, a plurality of trunk lines and a separate signaling path common thereto extending between said offices, responsive means at said distant office, a rotating switch automatically

controlled for associating said responsive means with any one of said trunk lines, means at said originating office for transmitting over the signaling path code signals individual to the different trunk lines for controlling the association of said responsive means with a particular trunk line, a normally inactive switching device common to the trunk lines for determining the code signals to be transmitted, and means controlled by a change in condition on one of the trunk lines for rendering the switching device active.

4. In a telephone system, in combination, an originating office, a distant office, a plurality of trunk lines and a signaling path common thereto extending between said offices, means at said originating office for establishing connection with any one of said trunk lines, a group of trunk finder switches at said distant office for seizing the incoming end of any one of said trunk lines, means controlled over said common signaling path for establishing a busy calling condition on the incoming terminals corresponding to a trunk line with which connection has been established at the originating office, and means automatically controlled over said common signaling path for initiating the movement of all idle switches of said group for causing the seizure of the trunk line upon whose terminals the busy condition appears.

5. In a telephone system, in combination, an originating office, a distant office, a plurality of trunk lines and a signaling path common thereto extending between said offices, means at said originating office for establishing connection with any one of said trunk lines, means at said originating office for transmitting over the signaling path codes of impulses individual to the different trunk lines, a normally inactive switching device common to the trunk lines for determining the codes of impulses to be transmitted, means controlled upon connection with one of said trunk lines for rendering the switching device active, means at the distant office responsive to said codes of impulses for establishing a busy calling condition on the incoming terminals of the trunk line which has been taken for use, a finder switch for establishing connection with the incoming terminals of any one of said trunk lines, and means automatically controlled over the signaling path for initiating the movement of said switch.

6. A plurality of transmission lines, a signaling path common to and independent of said lines, an automatic switch having movable terminals adapted to be automatically associated with any one of said lines, a source of impulses, means for transmitting impulses over the signaling path, and means responsive thereto for identifying a

selected line and for automatically operating the switch to associate the movable terminals thereof with said line.

7. A plurality of transmission lines, a 5 signaling path common to and independent of the lines, an automatic switch having movable terminals adapted to be automatically associated with any one of said lines, a source of impulses, an intermittently operating device for transmitting the impulses over the signaling path, and means responsive thereto for identifying a selected line and for automatically operating said switch for associating the terminals 10 thereof with said line.

8. In a telephone system, an originating office, a terminating office, a plurality of trunk lines interconnecting the offices, a signaling path common to and independent of 20 the lines, an automatic switching mechanism having movable terminals adapted to be automatically associated with any one of said trunk lines, means at the originating office for transmitting a code of impulses 25 over the signaling path, and means responsive thereto for automatically controlling the movable terminals of the automatic switching mechanism.

9. In a switching system, transmission 30 circuits extending between two stations, a signaling path extending between the stations and independent of said circuits, an

automatic switch having movable terminals adapted to be automatically associated with any one of said circuits, means responsive 35 to a changed condition of any one of said circuits to transmit a corresponding code combination over said signaling path, and means responsive to the received code combination to automatically control the terminals of said automatic switch to connect with a circuit having undergone a changed condition.

10. In a switching system, a plurality of transmission circuits extending between 45 two stations, a signaling path common to and independent of said circuits extending between said stations, an automatic switch having movable terminals adapted to be automatically associated with any one of 50 said circuits, means associated with each of said circuits at one of said stations for originating impulses, an intermittently operating distributor for transmitting impulses originating with any one of said circuits 55 over said signaling path to the second station for controlling the automatic switch to connect the terminals thereof with a circuit at which impulses have originated.

In testimony whereof, I have signed my 60 name to this specification this 7th day of August, 1920.

JOHN DAVIDSON, JR.
